Patented Oct. 7, 1975

237,088

DISPLAY STATION AND DATA COMMUNICATIONS TERMINAL

Walter W. Wiebe, 1915 Alexander Road,
Raleigh, N.C. 27608

Filed Apr. 25, 1974, Ser. No. 464,268

Term of patent 14 years

Int. Cl. D14—02

U.S. Cl. D26—5 C

FIG. 1

FIG. 2

FIG. 3

FIG. 4

FIG. 5

FIG. 1 is a perspective view of the front and left side of a display station and data communications terminal showing my new design.

FIG. 2 is a front elevational view thereof.

FIG. 3 is a right side elevational view thereof.

FIG. 4 is a rear elevational view thereof.

FIG. 5 is a bottom plan view thereof.

I claim:

The ornamental design for a display station and data communications terminal, substantially as shown.
